CLAIM

The ornamental design for a combined desk and hutch, as shown and described.

DESCRIPTION

FIG. 1 is an elevational right side, perspective view of my new design;

FIG. 2 is a right side perspective view thereof taken from a lower elevation;

FIG. 3 is a rear and right side perspective view thereof;

FIG. 4 is a front and right side perspective view thereof;

FIG. 5 is another right side perspective view thereof;

FIG. 6 is an enlarged right side elevational view thereof;

FIG. 7 is a plan view thereof;

FIG. 8 is an enlarged rear elevational view thereof;

FIG. 9 is an enlarged fragmentary sectional view taken along line IX—IX of FIG. 8, shown broken away for convenience of illustration;

FIG. 10 is an enlarged fragmentary elevation view of the top shelf taken along line X—X in FIG. 7; and,

FIG. 11 is an enlarged section view of the back panel and desk top taken along line XI—XI in FIG. 8, shown broken away for convenience of illustration.
